(57) **CLAIM**

The ornamental design for a handle for a kitchen knife, as shown and described.

DESCRIPTION

FIG. 1 is a perspective view of a first embodiment of the handle for a kitchen knife that comprises my invention;

FIG. 2 is a right side view thereof;

FIG. 3 is a left side view thereof;

FIG. 4 is a top view thereof;

FIG. 5 is a bottom view thereof;

FIG. 6 is a front view thereof, and

FIG. 7 is a rear view thereof.

FIG. 8 is a perspective view of a second embodiment of the handle for a kitchen knife that comprises my invention;

FIG. 9 is a right side view thereof;

FIG. 10 is a left side view thereof;

FIG. 11 is a top view thereof;

FIG. 12 is a bottom view thereof;

FIG. 13 is a front view thereof, and

FIG. 14 is a rear view thereof.

The broken lines depict environmental subject matter only

and form no part of the claimed design.
